UNITED STATES PATENT OFFICE.

JOSEPH HECTOR ELLINGSWORTH, OF WATERTOWN, ILLINOIS.

ADJUSTABLE SPLINT.

1,066,190.

Specification of Letters Patent.

Patented July 1, 1913.

Application filed January 6, 1913. Serial No. 740,414.

To all whom it may concern:

Be it known that I, JOSEPH HECTOR ELLINGSWORTH, a citizen of the United States, residing at Watertown, in the county of Rock Island and State of Illinois, have invented certain new and useful Improvements in Adjustable Splints, of which the following is a specification.

My present invention relates to improvements in adjustable splints for use in surgery, and is designed especially for setting the bones in remedying fractures of the lower limbs.

The essential object of the invention is the provision of a fracture apparatus which is easily adjustable, simple in operation, and may be quickly applied, and after being applied will be efficient in performing the functions required of this type of apparatus.

In the accompanying drawings I have illustrated one example of the physical embodiment of my invention constructed according to the best mode I have so far devised for the practical application of the principles of the invention.

Figure 1 illustrates the apparatus, or adjustable splint, applied as in actual use. Fig. 2 is an enlarged detailed, broken elevation, of a portion of the apparatus, partly broken away for convenience of illustration. Fig. 3 is a detail, sectional view of the lower end of the apparatus, as seen from a point at right angles to the view point of Fig. 2.

In the preferred embodiment of my invention I employ a tubular, metallic member 1, which is of suitable length and diameter, and while comparatively light in weight this member is sufficiently strong to perform its function as a splint. Into the upper open end of the member 1, a stem 2 is adapted to fit, and this stem is formed with a fork 3 or crutch, which conforms to the shape of the shoulder and is adapted to fit thereunder. The stem of the fork or crutch is adjustable in the tube or tubular member 1 and when so adjusted may be held in position by means of the set screw 4 which is threaded into the body of the tube 1.

Located at a suitable point on the tube 1 is a curved brace 5 which in actual practice is preferably brazed to the tube 1, and is perforated and threaded to accommodate the screw 6, which screw is provided with a head 7 and a knurled button 8. The screw is one feature or element of a lateral ten-

sioning device which includes a strap 9 buckled around the thigh, and provided with a coupling member or clip 10. The strap passes through an opening 11 in the clip, 60 and the head 7 of the screw 6 is loosely incased and free to turn within this clip. Above the thigh strap, a waist strap 11' is connected to the tube 1 by means of the staple or loop 12 which is loose and therefore slidable on the tube 1. A fixed loop 13 is arranged below the tension brace of the splint, and this loop is for the purpose of holding or securing the strap 14 which is buckled usually above the knee. 70

At the lower end of the tube 1, the material is cut out to form a slot for the accommodation of a rack wheel 15 which is journaled in the ears 16 integral with the tube. This wheel may be rotated by means of a 75 key 17 which is adapted to fit over the post 18 of the wheel journal. Within the lower end of the tube, a rack bar 18' is slideable, and in Fig. 3 it will be seen that the teeth 19 of the bar are engaged by the teeth of 80 the rack wheel 15, so that it will be readily understood that by means of the key as described, the rack bar may be projected from the tube, or made to recede therein, as desired. The rack bar is forked at its lower 85 end, and the tines 20 of the fork are attached, as by screws 21 to the steel sole 22. The shoe 23 of which the sole forms a part is adapted for use on either foot, and the sole is perforated at both sides for the 90 reception of the screws.

The shoe may be attached to the foot by means of the buckled straps 24 and 25 as clearly shown in Fig. 1.

The application of the apparatus is 95 clearly illustrated in the first figure of the drawing, wherein a fractured bone is indicated in dotted lines. The crutch portion of the splint is first placed up under the arm, and when properly adjusted, the set 100 screw is turned to secure the stem in the tube. The waist belt or strap is then adjusted about the waist, and the knee strap is buckled above the knee. The foot of the fractured limb having been incased and 105 buckled within the shoe, the splint is now ready for manipulation of the tension devices. Tension is placed upon the foot by turning the rack wheel to project the rack bar and steel sole from the tube. The shoe 110 being firmly attached to the sole, and the foot securely held within the shoe, it will

be clearly understood that the foot of the patient and his fractured member will move with the rod or rack bar and sole. The rack bar will be projected until the desired tension is secured, thus reducing the fracture, and the set screw is adjusted to hold the rack bar in distended position. Now by means of the screw 6 the lateral tension of the device is completed through the thigh strap, which movement completes the operation, leaving the parts at rest; and without likelihood of trouble resulting from undesirable movement on the part of the patient.

What I claim is:—

- 15 1. In an adjustable splint, the combination with a tubular member and a crutch member adjustable therein, an adjustable loop and a waist belt for attachment to the body; an integral arched brace, a screw in the brace, a coupling clip and a thigh strap for creating a lateral tension, and means for creating an axial tension.
- 20 2. In an adjustable splint, the combination with a tubular member and a crutch member adjustable therein, an adjustable loop and a waist belt for attachment to the body; an integral arched brace, a screw, a coupling clip and a thigh strap for creating a lateral tension; a lower section telescoping in the lower end of the tubular member, means for adjusting said section, and a shoe on said section.
- 25 3. An adjustable splint comprising a

tubular member having a telescoping section at each end, and means for projecting the lower end to create an axial tension, a strap adapted to encompass a limb and a screw bar threaded into a portion of the splint whereby a lateral tension may be created upon the limb through the strap.

4. An adjustable splint comprising a tubular member, a crutch member having a stem telescoping in said member, an axial tension device including a rack bar with a shoe attached thereto, said rack bar telescoping in the tubular member and a rack wheel on said member for projecting the rack bar, and a lateral tension device comprising a strap encircling the limb, an integral perforated brace attached to the tubular member, a screw bar threaded into said brace, and a loose coupling between said screw bar and strap.

5. The combination in an apparatus as described with a supporting member of an integral extension thereon, a screw bar threaded through said extension, a strap adapted to encircle the limb, and a loose coupling between said strap and screw bar, for the purpose described.

In testimony whereof I affix my signature in presence of two witnesses.

JOSEPH HECTOR ELLINGSWORTH.
